UNITED STATES PATENT OFFICE.

WILLIAM LESLIE DENHAM, OF BIRMINGHAM, ALABAMA.

AEROPLANE.

1,419,962.

Specification of Letters Patent. Patented June 20, 1922.

Application filed November 6, 1920. Serial No. 422,228.

To all whom it may concern:

Be it known that I, WILLIAM L. DENHAM, a citizen of the United States, and a resident of Birmingham, in the county of Jefferson 5 and State of Alabama, have invented certain new and useful Improvements in Aeroplanes, of which the following is a specification.

My invention is an improvement in aeroplanes, and has for its object to provide a 10 machine having planes mounted for rotation in a horizontal plane about a point fixed with respect to the fuselage of the machine, in order to exert a direct lifting force, to enable the machine to climb or descend upon 15 an even keel without tilting, as required in the present type of machine.

In the drawings:

Figure 1 is a top plan view of the improved machine,

20 Figure 2 is a side view,

Figure 3 is an enlarged sectional detail showing the connection between the guys and the track,

25 Figure 4 is a sectional detail showing the brake mechanism,

Figure 5 is a section on the line 5—5 of Figure 4.

In the present embodiment of the invention, a fuselage 1 is provided of any usual or 30 desired construction having at the front thereof the propeller 2 and having at the rear the vertical rudder 3 and the horizontal rudders 4. A super-structure in the form of a spherical or ovoid ring 5 is supported by 35 the fuselage, the plane of the ring extending longitudinally of the fuselage, and upon this superstructure there is mounted three tracks 6, 7 and 8, the track 8 being at the rear of the fuselage, while the track 7 is slightly above the center of the ring, and the track 6 is near the top. These tracks are circular, and the track 7 is double, consisting of similar 40 portions 7 and 7^a.

A series of wings is provided, each wing 9 45 consisting of upper and lower planes, spaced by struts and braced together as shown with the usual truss construction. These wings are arranged in two series, one series of four between the planes of the tracks 6 and 7, and 50 the other series also of four between the planes of the tracks 7 and 8.

The members of the series are arranged in vertical register, each wing carrying a motor indicated at 10, which drives the propeller indicated at 11. The wings of the upper se-

ries have their propellers arranged to drive the series as a whole in the opposite direction to the direction in which the planes of the lower series are driven by their propellers. That is, the upper series when in operation will rotate in the opposite direction to the lower series. These wings are connected to the three tracks rotatably by means of guys 12, 13 and 14. The guys 12 extend upwardly and inwardly from the upper 60 wings, while the guys 14 extend downwardly and inwardly from the lower wings.

The guys 13 extend inwardly from the upper and lower planes, and these latter guys are connected with mechanism which runs 70 upon the track 7. The guys 12 are connected with mechanism which runs upon the track 6, and the guys 14 are connected with mechanism which runs upon the track 8. Since all of this mechanism is similar, only that for 75 the track 7 is shown.

The mechanism for the guys 13 of the upper wings consists of a circular rim 14^a having ring 15 to which the guys are connected, and having a series of arms 16 extending in 80 the opposite direction to the rings, and each provided with a cross pin upon which grooved rollers 17 are journaled, the rollers being on the opposite sides of the arm.

Each of the tracks 6, 7 and 8 is a channel-shaped body, having the bottom of the channel secured to the super-structure 5 and having the side walls of the channel provided with inwardly extending flanges 18 forming tracks with which the grooved rollers 17 engage. The tracks 7 are so shaped that the wheels 17 will run smoothly upon the in-turned edges of the side walls of the channel, and the rim 14^a is curved transversely to fit about the track as shown.

A similar rim 19 is connected with the guys 13 of the lower wings, the said rim having the rings 20 with which the guys are connected, and the arms 21 which carry the grooved wheels 22. The rims for the guys 100 12 and 14 are in principle the same as those shown in Figure 3. All of these rims run smoothly upon the circular tracks when the wings are revolved about the super-structure.

105 Referring to Figure 1, it will be seen that the rims for the tracks 6 and 8 have eight rings for connection with the guys and eight sets of grooved wheels, one set being directly above the wings, and one set between 110

the wings. For the rims 14^a and 19 at the tracks 7, eight sets of wheels are provided, the sets being between the wings.

The wings of each series are connected by 5 a rim 23 with which the wings of each series are connected, the upper and lower planes being connected to the rim. These rims provide a rigid support for the wings, being securely trussed as shown to the inner 10 rims 14^a—19 and the rim at track 6 and track 8, and from which the wings extend radially.

In Figures 4 and 5, there is shown a 15 brake. With this arrangement a casing 24 is provided, which is secured to one of the tracks 7 or 7^a. Within this casing, there is arranged a plunger 25 having connected therewith a stem 26, and the plunger is normally pressed in one direction by a coil 20 spring 27 which encircles the stem between the plunger and the end of the casing. This stem 26 has a hook 28 at its outer end, and the hook is adapted to be engaged by a hook 29 on a lever 30 bearing on its opposite 25 end a wing or fin, said lever being pivoted to a bracket plate 31 on one of the rims 14^a or 19, that is, on that rim which is adjacent to the track carrying the casing. That is, 30 the end of lever 30 opposite the hook 29 is provided with a wing or fin. The arrangement is such that as the rim moves and the planes are in forward motion, the hook 29 on the bracket plate 31 carrying the fin or ring above described and which is fastened to the same rim as the planes and revolves in the same direction therewith, while the casing 24 is attached to the track, the air currents striking the fin or wing will 35 bear it down and raise the hook 29 clear of the casing 24, thereby allowing the hooks to pass over each other freely. Should the planes for any reason be stopped in mid air, immediately the fuselage with the planes, etc., would begin to fall, which would 40 cause a reverse motion to be set up by the planes and rims, bearing the hooks and in this way the air currents would then pick up the fin or wing, thereby lowering the hook 29 and bring it into engagement with the 45 hook 28 so as to stop the reverse motion of the plane. The spring 27 will be compressed, and the movement of the planes will 50 be braked. Upon the fuselage there is arranged at the rear thereof another propeller 55 32 which is provided for assisting the forward propeller when necessary, as for instance in turning or the like.

The motors carried by the wings are to be

driven electrically from dynamo located in the fuselage by means of trolley wires which 60 will encircle the super-structure. The motors will carry trolley wheels contacting with the trolley wires.

I claim:—

1. In combination, a fuselage having a 65 vertical super-structure, a series of tracks mounted on the super-structure, each track being circular and having its plane horizontal, a plurality of series of wings supported by the tracks and mounted to revolve 70 about the super-structure, means for revolving the upper series of wings, means for revolving the lower series of wings in the opposite direction, and means for propelling the fuselage forwardly, the tracks being 75 channel-shaped and having their channels outwardly and having the edges of the side walls turned inwardly to form bearing edges, rims encircling the tracks and having grooved wheels within the tracks and 80 engaging the inturned edges, and guys between the wings and the rims, the propelling means for the wings comprising independent motors, a motor being provided for each wing, and a propeller in connection 85 with each motor.

2. In combination, a fuselage having a 90 vertical super-structure, a series of tracks mounted on the super-structure, each track being circular and having its plane horizontal, a plurality of series of wings supported by the tracks and mounted to revolve 95 about the super-structure, means for revolving the upper series of wings, means for revolving the lower series of wings in the opposite direction, and means for propelling the fuselage forwardly, the tracks being channel-shaped, and having their channels outwardly, and having the edges of the side walls turned inwardly to form bearing 100 edges, rims encircling the tracks and having grooved wheels within the tracks and engaging the inturned edges, and guys between the wings and the rims.

3. In combination, a fuselage supporting 105 a series of superposed tracks having their planes parallel, a rim mounted to rotate about each track, each rim carrying a series of wings, said tracks being channel-shaped and having their channels outwardly, the 110 inside wall of each channel having an inwardly inturned edge, and the rims having grooved wheels engaging said inturned edges.

WILLIAM LESLIE DENHAM.
